INTERFERENCE REDUCING RADIO
SYSTEM

Norman H. Young, Jr., Jackson Heights, N. Y., assignor to Federal Telephone and Radio Corporation, Newark, N. J., a corporation of Delaware

Application April 16, 1943, Serial No. 483,360

12 Claims. (Cl. 250—6)

1
The present invention relates to radio transmission and reception, and more particularly to a method of, and means for, reducing interference with audio-frequency signals.

It is desirable to reduce the amplitude of any interfering or jamming waves which are received mixed with audio-frequency signals. The present invention provides a system whereby the audio-frequency signals are "chopped up" prior to transmission, and then restored at the receiving station to approximately their original form. However, any jamming waves also received are rendered ineffective by this restoring process.

Accordingly one object of the invention is to provide a method and means for periodically reversing the phase of an audio-frequency signal and then transmitting this periodically phase-reversed signal.

Another object of the invention is to provide a method and means for receiving a periodically phase-reversed signal and restoring the signal to its original form.

A further object of the invention is to synchronize the phase-reversing apparatus at the receiving station with the phase-reversing apparatus at the sending station through the use of means controlled by the frequency of phase reversal in the signal itself.

The invention has as a still further object a method and means whereby any received signal not periodically reversed in phase synchronously with the transmitted audio-frequency signal will be rendered ineffective to jam or interfere to any appreciable degree with such reversed audio signal.

Other objects and advantages of the invention will be apparent from the following description of one embodiment of the invention and from the drawings, in which:

Fig. 1 is a block diagram of a transmitting and receiving circuit embodying one form of the present invention;

Fig. 2 is a set of curves illustrating the operation of the circuit of Fig. 1;

Fig. 3 is a graph showing the operating characteristics of one of the elements of Fig. 1.

In the circuit of Fig. 1, voice-frequency signals from a source 2 are applied over a normal audio-frequency amplifier 4 to a phase-reversing device composed of a phase splitter 3 and an electronic switch 7. The phase splitter 3 is designed to produce two output waves, one of which is in phase with the input and the other 180° out of phase, as shown in Fig. 2 (B).

An oscillator 5 having a frequency of, say 2

kc. is provided, operating a square wave generator 6. The output waveforms of the oscillator and generator are shown in Fig. 2 (A).

The square wave output A from the generator 6 is used to control the operation of the electronic switch 7. This switch 7 produces a result similar to that of a conventional single-pole double-throw switch, in that it can be controlled to select either of the two output waves of the phase splitter 3.

When the square wave output A from generator 6 (having a 2 kc. frequency) is applied to operate the electronic switch 7, the switch will operate at the 2 kc. frequency to select alternately one of the two output waves from the phase splitter 3. In Fig. 2 the effect of control wave A on A. F. waves B is shown at C.

Thus due to wave A the phase of the audio-frequency signal from source 2 is reversed at the 2 kc. frequency of the oscillator 5 to result substantially in the waveform of Fig. 2 (C).

In Fig. 2 (B) an audio wave of fairly low frequency has been illustrated, resulting in a rather high number of phase reversals per cycle by the 25 2 kc. square wave A. If a higher frequency audio signal is taken as an example, then the number of phase reversals per cycle will obviously be lower. Nevertheless, if the audio-frequency 30 band has a maximum of say, 3000 cycles, then the audio signal will be "chopped" or reversed in phase at least once each cycle by the 2000 cycle reversing wave. This chopped wave is then applied to the usual modulator 8 supplied from a suitable high-frequency source 1 and from there 35 to a transmitter 9 where it may be transmitted on any desired frequency.

The receiver comprises first the usual receiver detector stage 10, and at the output of the receiver detector stage 10 is provided a 2 kc. band pass frequency filter and limiter 11. The limited portion of the 2 kc. frequency filtered off is then used to control a square wave generator 12 similar to the square wave generator 6 in the transmitter. The desired signals from the receiver detector 10 are applied to an amplifier 14 consisting of several stages, of which the first stages 21 may be of conventional design while the last stage will include a suitable electron discharge device 18 from which two output leads 19 and 20 are derived from the anode and cathode respectively. The lead 19 is derived from the anode of tube 18 in the usual manner to give the normal phase portions of the received wave without change. The lead 20 is connected to the cathode of tube

18 so that the phase-reversed wave portions appearing there will be transposed into normal portions like those appearing on the lead 19. In order to make the average potential of the outputs the same, the condensers C₁ and C₂ and the resistors R₁ and R₂ are so dimensioned that the time constants of C₁, R₁ and C₂, R₂ of the output network are sufficiently long.

The electronic switch 17 is similar in construction to the electronic switch 7 of the transmitter arrangement. The square wave output from generator 12 is applied to the electronic switch 17 to operate the switch synchronously with the frequency of phase-reversal of the transmitted signals, since the operating control frequency for the switch is derived from the transmitted signal itself.

Thus the switch 17 passes the output of lead 19 when the normally phased wave portions are appearing thereon, while it passes the output of lead 20 when the phase-reversed portions, now transposed to normal phase portions, are appearing thereon. A phase control 13 may be inserted as shown between the square wave generator 12 and the electronic switch 17 for the purpose of properly phasing the square wave with respect to the transmitted reversals. The output of the electronic switch 17 is then applied over a filter 15 to a sound reproducing device 16.

The wave received at 18 and partly reversed by the amplifier 16 and electronic switch 17 has the form shown in Fig. 2 (D), being substantially the form of the original wave before modification by the phase splitter 3 and electronic switch 7 of the transmitter.

With the above arrangement any jamming signals which are received will be chopped up in the receiver and reduced primarily to a 2 kc. and 4 kc. frequency. This is true because the disclosed system consists essentially of two circuits each designed to reverse the phase of a signal at a predetermined frequency. If the signal reversed by one circuit is then synchronously reversed by the other circuit, the reversals cancel one another and the original signal results. However, any wave applied directly to the second reversing circuit without being previously reversed in phase will be reversed in phase at the predetermined rate, and by proper filtering can be eliminated from the sound reproducing part of such second reversing circuit. If the normal transmitting band is arranged to run from, say, 200 cycles to 3000 cycles, then the filter 15 should have approximately the operating characteristics shown in Fig. 3, with a small portion of the band immediately adjacent the 2 kc. frequency being removed. This will not interfere with the intelligibility of the desired signals, but the amplitude of any jamming signals or other interference will be substantially reduced.

While I have described above the principles of my invention in connection with specific apparatus and particular modifications thereof, it is to be clearly understood that this description is made only by way of example and not as a limitation on the scope of my invention as set forth in the objects of my invention and the accompanying claims.

I claim:

1. In a radio circuit adapted to operate with an audio-frequency signal wave having periods of normally recurring phase reversal, the method which comprises deriving from said signal wave a control variation synchronized with said periods of normal phase reversal, and controlling the

modification of said signal wave by said variation during said periods.

2. The method of receiving a normally periodically phase-reversed voice-frequency signal which comprises separating from the received signal a wave indicative of the phase reversal frequency of the signal, and employing the separated indicative wave to control a modification of the received signal during the periods of normal phase reversal.

3. The method of receiving a normally periodically phase-reversed voice-frequency signal which comprises separating from the received signal a wave indicative of the phase-reversal frequency of the signal, employing the separated indicative wave to control the operating frequency of a wave generator, and then controlling a modification of the received signal by the output of the wave generator.

20 4. The method of claim 3, further comprising controlling the phase of the wave generator output with respect to the received signal.

5. In an interference-reducing radio circuit, means for receiving a periodically phase-reversed signal, a filter connected to said receiving means for obtaining from said signal a control wave having a frequency corresponding to the frequency of reversal in the phase of said signal, a phase-reversing device connected to said receiving means, means for employing said control wave to control the operation of said reversing device, a second filter connected to the output of said reversing device, and means for reproducing the signal output of said second filter.

35 6. Apparatus for receiving a normally periodically phase-reversed audio-frequency signal, comprising a receiver, a filter connected to the output of said receiver, a phase-reversing apparatus connected to the output of said receiver, a wave generator controlled by the output of said filter and controlling said reversing apparatus, a second filter connected to the output of said reversing apparatus, and a sound-reproducing device receiving the output of said second filter.

40 7. The apparatus of claim 6, further comprising a phase shifter connected between said wave generator and said reversing apparatus.

8. In a radio circuit, a receiver and detector, a phase-reversing amplifier connected to said receiver and detector, a band-pass filter and limiter connected to said receiver and detector, a square-wave generator, means for controlling said square-wave generator by the output of said band pass filter and limiter, a phase control in the output of said square-wave generator, means commutating the output of said phase-reversing amplifier by the output of said square-wave generator, a filter connected to said phase-reversing amplifier, and a sound-reproducing device connected to said filter.

9. In a signal system, a source of audio signals, means for periodically reversing the phase of said audio signals, means for controlling the frequency of operation of said phase-reversing means, means for transmitting and receiving said periodically phase-reversed signals, means for separating from said received signals a control variation varying in frequency synchronously with said first-mentioned means, means for periodically reversing the phase of said received signals, means for controlling the periods of operation of said last-mentioned means by said control variation, and means for modifying said received and phase-reversed signals to cause them

to correspond approximately to those produced by said source.

10. Apparatus for receiving a normally periodically phase-reversed audio-frequency signal, comprising a receiver and detector, a filter connected to the output of said receiver and detector, a multi-stage amplifier connected to the output of said receiver and detector, said amplifier including an electron discharge device having an anode, a cathode, and a grid in the last stage thereof, means for deriving the normally phased portions of the periodically phase-reversed audio-frequency signal output of said receiver and detector from the anode circuit of said electron discharge device, means for transposing into normally phased portions the phase-reversed portions of said audio-frequency signal appearing in the cathode circuit of said electron discharge device, an electronic switch selectively connected to the anode and cathode circuits of said electron discharge device, a square-wave generator, means for controlling the frequency of operation of said square-wave generator by the output of said filter, a sound-reproducing device, means for controlling the operation of said electronic switch by the output of said square-wave generator to cause said switch to connect alternately said sound-reproducing device to the anode and cathode circuits of said electron discharge device, and a second filter connected between said sound-reproducing device and said electronic switch.

11. Communication system comprising, an alternating current signal source, means periodically reversing the phase of said signal source, a carrier wave source, a modulator fed by said carrier wave source, an electronic switch for alternatively connecting the outputs of said phase reversing means to said modulator for modulating said carrier, an oscillator, a square

- wave generator controlled by said oscillator and keying said electronic switch, means for transmitting said modulated carrier, and receiver means including a demodulator, phase splitting means and a band-pass filter of the frequency characteristic of said oscillator both fed from said demodulator, signal reproducing means, a second electronic switch, alternatively interconnecting the outputs of said phase splitting means with said signal reproducing means, a second square wave generator connected to and controlled by the output of said band-pass filter, and means controlling the operation of said second electronic switch by said second square wave generator.
- 15 12. The combination according to claim 11, in which said phase splitting means comprises an amplifier, and means deriving signals of opposite phase from the output stage of said amplifier.
